UNITED STATES PATENT OFFICE.

OTTO S. MARCKWORTH, OF COLUMBUS, OHIO.

LAMINATED ARTICLE.

1,368,954.

Specification of Letters Patent. Patented Feb. 15, 1921.

Application filed April 24, 1919. Serial No. 292,493.

To all whom it may concern:

Be it known that I, OTTO S. MARCKWORTH, a citizen of the United States, residing at Columbus, in the county of Franklin and 5 State of Ohio, have invented new and useful Improvements in Laminated Articles, of which the following is a specification.

This invention is a laminated article of manufacture of the type of the so-called 10 non-shatterable glass.

One of the objects of the invention is to provide a covering for table and desk tops, wall panelings, toilets, and the like, capable of replacing marble, or the thick, brittle 15 white glass plates which are now in vogue. A further object is to provide a laminated article of the character mentioned in which ornamental elements may be embedded. A further object is to provide a laminated article in which specimens of any character, 20 photographs, documents and the like, may be embedded for preservation, display or advertising purposes.

The invention will be hereinafter fully 25 set forth and particularly pointed out in the claims.

In the accompanying drawing: —

Figure 1 is a plan view illustrating a non-shatterable glass member with a piece of 30 lace embedded therein. Fig. 2 is a cross sectional view thereof. Fig. 3 is a plan view illustrating a non-shatterable glass member with a written document embedded therein for preservation. Fig. 4 is a similar view 35 illustrating the method of embedding specimens for display and protection. Fig. 5 is a sectional view thereof.

Referring to Fig. 1 of the drawing, 10 designates a body of non-shatterable glass, 40 constructed of two laminæ 11 of ordinary glass, united by a non-shatterable element 12, and having embedded therein an ornamental article such as a piece of lace 13.

The laminæ may be united in any well 45 known manner conforming to the practice of manufacturing non-shatterable glass, but it is preferred to follow the method disclosed in the copending application filed March 26th, 1919, Serial #285,348. As 50 pointed out in the said copending application an excellent non-shatterable glass is provided by uniting layers of glass and celluloid after they have been immersed in a celluloid solvent which is normally inactive 55 but which is rendered active for a sufficient

period to produce the desired binding effect without injury to the celluloid. The specific solvent disclosed in the said copending application for patent consists of propyl, butyl, or amyl alcohol or their mixtures, 60 combined with camphor and most any one of the essential oils, especially oil of citronella, oil of cloves, or methyl salicylate. In practising the present invention a plate 11 of glass is immersed in the solvent solution, a sheet of celluloid 12 is then immersed on top of the glass, then the piece of lace 13 is positioned, after which another sheet of celluloid is placed on top of the lace, and finally another piece of glass is placed in 70 position. After the laminæ have been removed from the bath, the excess of the solution is squeezed out from between the laminæ, and the whole subjected to pressure at the proper temperature to secure the desired action of the solvent. The pressure applied is preferably at the rate of from fifty to four hundred pounds per square inch of surface, depending upon the character of 75 the material.

The article illustrated in Fig. 3 is constructed in identically the same manner as the article illustrated in Fig. 1, but if the document is of a nature which needs to be protected from the action of light, the celluloid laminæ may be selected from the stand-point of color or actinic-ray absorption, so as 80 to protect it completely.

In the forms illustrated in Figs. 4 and 5 the glass member 14 is molded with a cavity 90 15, to receive the specimen 16, the celluloid members 17 being provided with openings to accommodate the specimen, the weld taking place between the flanges 18 of the glass members 14.

An article of manufacture such as herein described is susceptible of many variations and wide use, and no attempt has been made to illustrate all of the forms of the invention. For instance opaque sheets of colored 100 celluloid may be employed as the celluloid laminæ if an opaque glass is desired, or celluloid which has been lithographed or in any way dyed, or carrying designs of any character may be employed, and could frequently 105 be handled in single sheet form. The invention is capable of many other uses such as the preservation and mounting of photographs, for the making of permanent lantern slides and transparencies and other 110

objects of a similar nature. A further advantage of the invention is that the solvent solution employed for uniting the laminæ has distinctly preservative and antiseptic qualities, and being neutral, non-corrosive and harmless in every way, it is adaptable for every conceivable purpose where the embedded article is to be preserved. Other forms of the invention may be embodied in 10 colored table tops, desk tops, wall panelings, toilets, etc., or in lieu of the material of solid color, tapestries, laces, linens, etc., may be embedded between the laminæ, portions of the sheets of glass could be left 15 transparent at will by interposing a lace article such as a doily, in the case of a dressing table, or of a piece of linen to represent a table cloth or other table cover.

Having thus described the nature of the 20 invention and explained an operative manner of constructing and using same, although without attempting to set forth all of the forms in which it may be made, or all of the forms of its use, what is 25 claimed is:—

1. A laminated article comprising transparent laminæ of non-shatterable glass having embedded therein an article of foreign material.
2. A laminated article comprising transparent laminæ of non-shatterable glass pro-

vided with an embedded display element visible through the glass.

3. A laminated article comprising transparent laminæ of non-shatterable glass having means for controlling the amount of light passing therethrough, and provided with an embedded display element visible through the glass. 35

4. A laminated article comprising glass 40 and celluloid laminæ permanently united, and a display element interposed between the celluloid laminæ.

5. A laminated article comprising glass and celluloid laminæ permanently united, 45 and a display element interposed between the celluloid laminæ, said celluloid laminæ being of a color to resist actinic effect of light.

6. A laminated article comprising glass laminæ chambered to receive an article to be 50 displayed, and celluloid laminæ permanently uniting the glass laminæ and inclosing said article.

7. A laminated article comprising laminæ of glass and celluloid, an interposed solvent 55 binder of a nature incapable of destroying the transparency of the celluloid under normal atmospheric conditions, and a display article embedded between said laminæ.

In testimony whereof I have hereunto set 60 my hand.

OTTO S. MARCKWORTH.
